UNITED STATES PATENT OFFICE.

HENRY A. GOETZ, OF NEW ALBANY, INDIANA.

SEWER CLEANER AND FLUSHER.

1,081,497.

Specification of Letters Patent. Patented Dec. 16, 1913.

Application filed January 24, 1910. Serial No. 500,844.

To all whom it may concern:

Be it known that I, HENRY A. GOETZ, a citizen of the United States, residing at New Albany, in the county of Floyd and State of Indiana, have invented certain new and useful Improvements in Sewer Cleaners and Flushers, of which the following is a specification, reference being had therein to the accompanying drawing.

10 This invention relates to improvements in machines and devices for cleaning and flushing sewers.

The objects of the invention are to provide a machine which will be automatically propelled through a sewer and which will have means for loosening the material from the surface of the sewer, and means for flushing the sewer to carry away the loosened material.

20 Other objects relate to the various features of construction and arrangement of parts which are fully shown in the drawings and described in the following specification.

25 Of the drawings, Figure 1 is a cross sectional view of a section of sewer showing a machine embodying my invention in operation. Fig. 2 is an end view showing a machine in position in a sewer. Fig. 3 is a 30 cross sectional view showing a machine in position in a sewer.

Referring to the drawings, 1 represents the sewer cleaner and flusher as a whole. The machine is preferably provided with 35 three supporting wheels, 2, 2, and 3. The wheel 3 is located in the center of the machine, near the rear end. The forward wheels 2, 2, are mounted at an angle of about 120° to each other, and lie in planes which 40 intersect at the axis of the sewer. These wheels are also provided with worm teeth 4, which enables them to exert a greater tractive effort upon the surface of the sewer. The worm teeth 4 also serve to rotate the 45 wheels by their engagement with the worm which will be hereafter described.

50 5 represents the casing and main frame of the machine. This is preferably formed in two parts 5^a and 5^b which are joined together by bolts passing through the vertical flanges at 6. The casing is provided with an approximately semi-cylindrical wall 7 concentric with which there is mounted on the shaft 8, the runner 9. The shaft 8 is freely 55 rotatable in suitable bearings on the casing.

10 represents a nozzle connected to the

casing 5. To this nozzle there is connected by means of the coupling 11 a hose 12.

The runner 9 is provided with a series of buckets or blades 13 which extend substantially radially outward from the hub of the runner. These buckets are adapted to receive the impact of the water passing through the nozzle 10 and are preferably concaved toward the nozzle. It will be 65 noted, however, that the concavity is slight and is not sufficient to give to the wheel a maximum hydraulic efficiency, such as might be obtained by using buckets of the Pelton type. The reason for the form of bucket 70 which is used will be more fully set forth hereafter.

On the hub of the wheel, inside of the path of the buckets, I provide bevel gear teeth 14. On the frame or casing 5, in a 75 suitable bearing 15 is mounted the shaft 16. At the rear end of this shaft there is provided a bevel pinion 17 which is adapted to mesh with the gear teeth 14 on the hub of the runner. The worm 18 is secured to the 80 shaft 16 in advance of, and adjacent to, the bearing 15. The worm 18 is of such a size and pitch that its threads will engage with the worm teeth of the driving and supporting wheels 2, 2. To the forward end of the 85 shaft 16 there is secured an arm 19 which carries the knife 20. The arm 19 is of such a length that the knife 20 will be moved either in contact with, or closely adjacent to the surface of the sewer. The forward end 90 of the knife 20 is preferably curved inward to permit it to more easily pass over any irregularities of the sewer surface as the machine is advanced. Suitable brackets for the wheel 3 such as indicated by 21 and 22, 95 and suitable brackets for the wheels 2, 2, such as indicated by 23, 23, are provided either as integral parts of the casing and frame 5, or are rigidly attached thereto.

At the top of the machine I prefer to provide a wheel 24 which is adapted to engage with the upper surface of the sewer. This wheel is connected to the main frame by means of an elastic arm 25. By means of the screw 26 the angle of the arm 25 relative 100 to the main frame may be changed and the arm flexed to cause a pressure of the wheel 24 against the upper surface of the sewer. This pressure may be regulated by adjusting the screw 26.

105 The operation of the sewer cleaner and flusher is as follows: The machine is first

lowered into the sewer through a manhole such as is shown at 27. The machine should preferably be started at the lower end of a sewer and should work toward the upper end. When the machine has been placed in position for operation, the hose 12 is connected to it and the other end of the hose is connected to a hydrant. The hose should preferably be provided with suitable supporting wheels such as 28, which serve to hold it out of contact with the sewer and to permit it to readily be moved along. When water is admitted to the hose under pressure, it passes through the nozzle 10 with considerable velocity and impinges against the buckets or blades 13, thus imparting a rapid rotary motion to the runner 9. By means of the gears 14 and 17, the rotary motion of the runner is communicated to the shaft 16 and the worm 18. The worm 18, by its engagement with the wheels 2, 2, causes them to rotate, and their engagement with the walls of the sewer advances the machine. The arm 19 with the knife 20 being connected to the shaft 16, is rapidly revolved, the knife 20 cutting and loosening all material from the surface of the sewer and causing it to fall to the bottom. In many cases it is found that roots of trees have grown into the sewer and these frequently greatly retard the flow of sewage. The knife 20 is driven with sufficient force and velocity to cut off any such roots. The water which enters through the nozzle 10, after acting on the wheel is discharged toward the bottom of the sewer and in a direction slightly inclined toward the rear. Owing to the form of the runner blades the whole energy of the water is not utilized and it is discharged against the bottom of the sewer with considerable velocity. The water thus discharged serves to still further loosen and break up material, and the material so loosened and broken up is carried away toward the rear by the stream of water. When the machine has advanced to another manhole such as 29, it may be stopped and the hose removed and drawn backward through the manhole 27. The hose may now be passed through the manhole 29 and again connected to the machine, the operation before described being repeated. The wheel 24 serves to hold the machine in position and also gives increased tractive pressure to the wheels 2, 2. The three wheeled mounting which I have provided gives the machine a firm support in spite of any irregularities which may exist in the contour of the sewer.

60 A machine embodying my invention is of course especially adapted for use in sewers which are circular in cross section. It is obvious however, that with some modifications, machines of this type may be used in 65 sewers of non-circular cross section and I

consider my invention as extending so far as applicable to machines adapted for use in non-circular sewers. For instance in sewers which are "egg-shaped" in cross section, very little change in my machine would be necessary although it would be impossible for the knife 20 to clean any of the surface except the partly cylindrical portion at the bottom. 70

What I claim is:—

1. In a machine for cleaning sewers the combination of a hydraulic motor, means for supplying water to the motor, propelling means connected to the motor, and the exhaust opening of said motor directed to discharge water against the sewer surface in a direction inclined oppositely to the direction of motion of the machine, substantially as set forth. 75

2. In a device for cleaning sewers the combination of propelling means, means for supplying water to the device and means for discharging water from the device against the sewer surface in a direction inclined oppositely to the direction of motion of the device, substantially as set forth. 80

3. In a machine for cleaning sewers, the combination of a motor and two supporting and propelling wheels connected to said motor and lying in diverging planes, substantially as set forth. 90

4. In a machine for cleaning sewers the combination of a motor, two propelling wheels connected to the motor and lying in diverging planes, and an elastically mounted wheel adapted to engage with the upper surface of the sewer, the axes of the three wheels located in the same plane perpendicular to the axis of the sewer, substantially as set forth. 100

5. In a machine for cleaning sewers, the combination of suitable cleaning means with a plurality of supporting and guiding wheels, three of the said wheels located in diverging planes with their axes in the same plane perpendicular to the axes of the sewer, said wheels located at the forward end of the machine, and a follower guide wheel mounted at the rear end of the machine. 105

6. In a machine for cleaning sewers the combination with suitable cleaning means of a hydraulic motor with its axis located transverse the axis of the sewer, a rotatable shaft parallel to the sewer, power connections between the shaft and the motor, a worm mounted on the said shaft and a worm wheel having teeth adapted to engage with the said worm, said wheel being also adapted to engage the surface of the sewer to propel the machine, substantially as set forth. 115

7. In a sewer cleaner the combination of propelling means, a cutting and cleaning device at the forward end, and means for supplying a stream of water to the sewer in a 120

125

130

direction opposite to the motion of the device and behind the said cutting and cleaning devices, substantially as set forth.

8. In a sewer cleaner the combination of a
5 motor adapted to discharge water at an angle to the surface of the sewer in a direction opposite to the motion of the cleaner and suitable cutting and cleaning devices in

advance of the motor and connected thereto, substantially as set forth. 10

In testimony whereof I affix my signature, in presence of two witnesses.

HENRY A. GOETZ.
